COIN CHUTE

Walter A. Tratsch and William Patzer,
Chicago, Ill.

Application September 18, 1936, Serial No. 101,418

12 Claims. (Cl. 194—101)

This invention relates to coin chutes and more particularly to the type of chute having combined automatic and manually operable detecting and ejecting means for rejecting spurious coins, 5 the instant disclosure being a continuation, in part, of our co-pending application Serial No. 85,879, filed June 18, 1936, for coin and slug separating device.

Only so much of the structure of the mechanism shown and described in the said co-pending application will be set forth herein as may be necessary for an understanding of the structure and operation of the present disclosure.

Coin chutes of the general class to which the 15 present disclosure pertains include, generally, a chute member having a coin path with entrance and exit openings and various selecting and ejecting mechanisms interposed in the path of a coin in its movement between the said entrance and exit openings.

Mechanisms of the aforementioned general type may include a magnetic member in the coin path against which a paramagnetic coin will be attracted in actual contact, and still other magnetic members adapted to maintain a magnetic flux across the path of the moving coin. In general, the present disclosure is concerned with improvements in a coin chute mechanism of the latter generally described type.

30 It has been discovered that for reasons at present not ascertained, certain otherwise legitimate coins such as certain of the United States five-cent or nickel pieces, are attracted and stopped in their passage through the chute by the flux maintaining magnets, thus jamming or choking the chute against normal movement of coins therethrough.

It has further been discovered that a practice exists of providing so-called slugs and other 40 coin simulating bodies with central fill-in portions of iron or other paramagnetic substances, and coins or slugs of this latter type are readily attracted and held against movement in the magnetic field maintained across the chute path as aforesaid.

It is an important object, therefore, of the present invention to provide a manually operable means for ejecting or clearing from the chute 50 both the spurious and legitimate coins which may be held against movement by the flux maintaining magnetic members commonly provided in present day types of coin chute.

A further important object is the provision of 55 an optionally operable slug clearing mechanism

for use with types of coin chute having a manual ejecting or clearing control.

Other and more specific objects will appear in view of the following detailed description, together with the drawings in which:

Fig. 1 is a side elevation of a chute mechanism incorporating the novel means of the present invention.

Fig. 2 is a front elevation of the device of Fig. 1 and taken along the lines 2—2 thereof;

Fig. 3 is a horizontal section through the lower part of the chute mechanism of Fig. 1, and taken in the direction of lines 3—3 thereof;

Fig. 4 is a median vertical section taken along the lines 4—4 of Fig. 2;

Fig. 5 is a vertical section taken along the lines 5—5 of Fig. 4; while

Fig. 6 is a diagonal section taken along lines 6—6 of Fig. 4.

The body structure of the coin chute shown in Fig. 1 comprises a main side wall plate 10 having on its inner surface a cut-away or channeled chute or coin path 12 (Fig. 4), which may be extended in a tortuous and descending direction toward the lowermost extremity of the plate 10 to open into two exit or discharge openings 14 and 16 in the said lower edge. As shown in Fig. 5, the said main side wall plate 10 is provided with a closure plate 18 hinged as at 21 for movement toward and away from the chute body so as to provide a movable side wall section and opening the chute portion 12 being otherwise substantially closed except for the aforementioned discharge openings 14 and 16, and an entrance or deposit opening 20 in the upper region of the chute and an intermediate side opening 43.

Supported upon the main plate member 10 by means of lugs 22 and 24 in slots in the top edge of the chute body and pivoted upon extensions 21' from the chute body, is a magnet bearing plate 26 (Fig. 1) in which is clamped an elongated bar magnet 28 by means of a plate having extended fingers 23 protruded through apertures in the plate 26 and a clamping screw 25 securing the two plates together. The magnet 28 has a plurality of edge portions 30, one of which is adapted to extend through the carrier plate 26 and through longitudinal opening 32 in the side wall of the chute, slightly into the upper longitudinal region of the coin chute or passage (Fig. 4).

This magnet bearing plate 26 is adapted to move outwardly on hinge rod 21 from the chute

wall 10 by means of a manual control to be hereinafter particularly described.

Substantially parallel with the protruding edge 30 of the magnet 28 in the opening 32 is a very low ridge or lateral extension 34 on the inner surface of the chute and against which a coin descending the upper chute level may bear in passing or engaging the magnetic edge portion 30. Protruding into the chute wall from the exterior walls thereof is a pair of pin members 36 adapted to be moved into the channel or chute path by tilting the chute mechanism for the purpose of deflecting the normal downward descent of the coin. Immediately below the aforementioned pins 36 is an anvil 40 of predetermined hardness and rebound characteristics, such that a legitimate coin striking thereon after movement from the entrance opening 20 will be deflected against a light wire hinge member 42 to pivot the latter as at 44, and move into the lower region of the chute for passage between the pole pieces 45 of a pair of permanent magnets 46 mounted on the outer surface of the chute body adapted to maintain a constant magnetic field across the path of a descending coin for purposes of variously affecting the speed of movement of coins or tokens or varying metallic and paramagnetic characteristics.

Also positioned within the chute in a direction below the pole pieces 45 is a pair of adjustable deflecting members 48 and 50 against which coins may impinge for deflection, depending upon their metallic content and hardness, toward one or another of the exit openings 14 or 16.

35 The selective scavenging or clearing mechanism of the present invention is shown in part in Fig. 4 to include a coin ejecting finger 52, in the shape of an arcuately conformed plate having a nose portion 54 and pivoted as at 56 in a cut-away portion 58 of the main chute plate 10 for movement of the nose portion 54 thereof through a cut-away opening 60 in the longitudinal edge of the plate 10 into the chute path to assume the dotted line position shown in Fig. 4. 45 Referring again to Fig. 1, the ejecting finger 52 is pivotally connected at 63 with a bell crank 62 also pivoted at 56 upon the outer surface of the side wall plate 10, and has a laterally extended stopping pin 64 adapted to be moved 50 against the side edge of plate 10 to limit the movement of the finger inwardly.

55 A drive rod or plate 66 is slidable on a pair of pins 68 and 69 extended laterally from the side wall 10 into a pair of longitudinally extensive slots 70 in the plate 66. The pin 69 extends outwardly of the plate 10 beyond the extremity of the pin 68 and has attached thereto a spring 72 which is attached at its other extremity to an outwardly extending pin 74 on the bell crank 62; the left-hand extremity 67 of the rod 66 normally bears against the pin 74 of the bell crank under the urging of the spring 72, while the opposite extremity of the rod 66 is connected with a pivot arm 76 by means of a headed screw pin 65 77 extended through a longitudinal slot 78 in the arm 76 and threadable into the body of rod 66.

70 It should also be observed that there is a third lateral slot 61 in the side wall plate 10 underlying the slide bar 66. This slot communicates with the interior of the chute at the lowermost region of the passage adjacent the rebound deflectors 48 and 50. (See Fig. 4.)

75 Extended laterally of the slide rod 66 is a pin 65 which protrudes into the chute passage

(Figs. 1 and 4), and in its normal position, corresponding to the normal position of the slide bar 66, this blocking pin 65 abuts the extremity of slot 61 (right-hand in Fig. 1, left-hand in Fig. 4) so that its inner extremity lies below the deflector 48, out of the path of moving coin elements.

80 The arm 76 is pivoted on the side wall plate 10 as at 80 and has a second diverging arm 82 with a sidewise extension 84 which confronts the front lateral wall or edge 86 of the chute structure as in Fig. 2, and which has a diagonally extending cam surface 88 for camming engagement with the lower extremity 90 of a master ejecting arm 92 pivoted as at 94 on the edge- 15 wise extremity 86 of the chute.

85 The master ejecting arm 92 has a companion arm 96 pivoted as at 98, adjacent the arm 92 and having an arcuately shaped recess 100 in an extended part thereof into which is movably extended a boss 102 on arm 92.

90 Coil spring 104 has its extremities attached to the uppermost extremities 95 and 93 of the ejecting arms 96 and 92 respectively, to draw the latter toward each other and toward their respective side walls 10 and 18 of the chute structure.

95 The companion arm 96 has a laterally extended pin 108 which overlies the upper endmost portion of the side wall 10 for engagement with an extended loop portion 21 on the magnet carrier 26, for the purpose of pivoting the latter on its hinges 22 in a direction away from the side wall 10 when arm 96 is pivoted responsive to a movement of the master arm 92. (See Figs. 1 and 2 particularly.)

100 The side wall 18 of the chute body has a pivotally movable portion adapted to be moved away from the plane of the common body portion by engagement with an extension thereof of the pin 99 on arm 92 for the purpose of 40 permitting certain types of spurious coins or tokens to be discharged in a sidewise direction from the chute proper after they have been detected or detained by the various detecting mechanisms provided in the chute, examples of which 45 will be mentioned in the appended description of operation.

105 It being desirable to provide a manually or selectively operable means for returning spurious coins or slugs to the depositor and otherwise to clear the coin chute of such undesirable elements, I have provided a manually operable plunger 112 which is slidable against the spring 114 in a mounting sleeve 116 extended through the wall 8 of the cabinet of a vending machine 55 or like device with which the coin chute is associated. The innermost extremity of the plunger rod 112 is provided with a suitable head 118 which confronts an edge portion of the lower extremity 90 of the master ejecting arm 92, the 60 chute structure being secured to the wall 8 adjacent the plunger mechanism as shown in Fig. 2.

Operation

110 Referring first to Fig. 4, it may be assumed that a legitimate coin is deposited in the receiving opening 20 of the chute whereupon the coin will descend past the edge 30 of a first testing means or magnet protruding into the said wall opening 32, past the deflecting pins 36, and 70 downwardly to strike upon the anvil 40. Being a legitimate coin it will rebound from the anvil suitably to pass the light gate 42, moving the latter about its pivot 44, and continuing on downward past the confronting pole pieces 45 of a 75

second testing means in the form of magnets 46 and through the magnetic field created by the latter, after which it will finally strike upon the deflecting point of the deflector 50 and be discharged through the exit 14.

Assuming a spurious non-metallic or other light slug, made for example of cardboard, to be inserted at the opening 20, it will move downwardly in the chute and if it is sufficiently light will be substantially halted in its downward movement upon striking the anvil 40 sufficiently to fall into a depression 41, and thereafter it may be ejected through the intermediate side wall opening 43 into a discharge chute 47.

In the case where a light weight cardboard or the like slug rebounds from the anvil 40 with sufficient force to pass the depression 41, it will strike against the gate member 42 and in all probability be thrown back thereby into the depression 41, or in the event such a slug succeeds in passing the gate 42 it will ultimately be disposed of through a proper rejecting exit 16 by means of the deflecting member 48 and 50 in the lower region of the chute.

In the case where a paramagnetic coin is inserted in the receiving opening 20, such coin in all probability will be immediately halted in its downward course by attraction against the protruding edge 30 of magnet 28, there to remain until the plunger rod 112 is urged inwardly against its spring 114 to move the master arm 92 and its companion arm 96 so that the latter may pivot the magnet bearer 26 outwardly to disengage the retained coin and permit the latter either to fall out the side wall exit created by outward movement of the gate or movable side wall section 18, which opened simultaneously with the operation of the carrier 26, or the released token will resume its downward movement, which movement because of the arrest of its descent will in all probability cause the coin or slug to rebound from the anvil in a manner to deposit it in the depression 41 to pass out exit 43. Such coin, however, should it not be rejected in the upper region of the chute, in all probability would be discharged through the exit 16 because of the effect of the magnetic field set up by magnets 46 upon its downward momentum and the deflecting effect of the member 50.

A paramagnetic coin which has passed the magnet 28 in the upper region of the chute may be frequently attracted toward one or the other of the pole pieces 45 of magnets 46 should such a coin or slug descend that far in the chute. In such a case, the attraction of the coin may be sufficient to prevent dislodgment or movement by other coins subsequently deposited, and thus the mechanism would be substantially jammed and inoperative.

In the general types of coin chute mechanism heretofore used and having selecting and detecting instrumentalities corresponding generally to those herein described, there would be no means for clearing the device other than disassembling the coin chute structure to remove the attracted slug. The means of my present invention provides a mechanism which makes it unnecessary to resort to such an expediency.

Assuming a coin, whether legitimate or spurious, be held between the pole pieces of the magnets 46, the operator or the proprietor of the device may readily clear the machine by depressing the plunger 112 and thus causing the headed portion 118 thereof to bear against the lower edge of the master ejecting arm 92, where-

upon the latter will be pivoted in a clockwise direction about the pivot 102 to cause the lower cam extremity 90 thereof to move over the inclined cam surface 88 and thus pivot the arm 16 (see Fig. 1) downwardly and move the sliding rod or plate 66 in a direction toward the left, so that the extremity 67 thereof will bear against the pin 14 and move the bell crank 62 about the pivots 56 in a clockwise direction, thus urging the ejecting finger 52 through the pivoted linkage 63 in an inward direction about its pivot 56 until the nose portion 54 of the finger assumes the dotted line position shown in Fig. 4, in which position a coin C may be struck and dislodged from the attraction of the magnets 46 for further descent in the chute toward the spurious-discharge opening 16, or the coin may merely be slid downwardly a short distance without dislodgment.

The foregoing movement of slide bar 66 will also have caused the blocking pin 65 to be carried from its ineffective position beneath the deflector 48 to the right-hand end of the slot 61 (Fig. 4) and into the path of descending coin elements, thus assuring that the latter (legitimate or spurious) will be deflected into exit 16.

Thereafter the operator may release the plunger 112 for restoration by means of the now compressed spring 114 to its normal position of Fig. 2. The master ejecting arm 92, together with its companion arm 96, will likewise be restored to normal position (full lines in Fig. 2) by means of the spring 104.

However, should a coin or slug C' (dotted lines Fig. 4) be halted near the lowermost pole pieces 45, it will be apparent that the ejecting finger 52 when pivoted into the dotted line ejecting position of Fig. 4, would not contact such coin and would be ineffective to dislodge the latter. In such a case, the subsequent deposit of a legitimate coin or one that for any reason was permitted to pass to the lower region of the chute into position behind the coin C' (which position may also be represented by the coin C of Fig. 4), then the nose 54 of ejecting finger 52 would contact the latter (coin C) of the two coins or slugs and dislodge both retained coin elements for subsequent discharge through the opening 16 or 14, unless both be paramagnetic, in which case the latter might remain attracted but would be displaced.

In the event that a coin element C'' (also shown in dotted lines in Fig. 4) should line up behind one or more retained coins C' or C, or otherwise be held in its indicated position, such coin element will likewise be dislodged by the finger 52 upon operation of the plunger 112.

We have thus provided an additional scavenging or slug clearing mechanism cooperable with an existing novel form of manually operable clearing mechanism, and one which is simple, rugged, and cheap in construction and which may be readily applied to coin chutes of the class generally described, such mechanism being particularly effective to return to the operator or proprietor of a vending machine with which it may be associated, various types of coin elements, both legitimate and spurious, when such elements are selected or retained within the coin chute mechanism under any of the several conditions herein suggested.

While we have described in detail a particular embodiment of our invention for purposes of illustration, it is not our intention to be restricted to such details except in such manner as may be hereinafter provided in the appended claims.

We claim:

1. A gravity type coin chute including a first magnetic testing means normally positioned to arrest certain coin elements in said chute and mounted for movement from said normal position to free coin elements arrested thereby, means in said chute providing a discharge opening adjacent said first testing means and through which coin elements freed as aforesaid normally pass out of the chute, means for effecting movement of said first testing means into and out of normal position, a second magnetic testing means spaced away from said first-mentioned testing means for selectively affecting the rate of movement of coin elements through said chute, ejecting means including a finger mounted for movement from a normal unobstructing position into the coin path in the chute to dislodge coin elements retained therein by said second testing means for continued movement of the dislodged element down the passage, means operably connecting said ejecting finger means with said means for moving the first testing means for ejecting operation with the latter, together with means positioned at a point in said chute below said second testing means for cooperation with the latter to selectively deflect coin elements descending from higher levels.
2. A coin chute having a descending chute passage and magnetic testing means mounted for movement relative to said passage and normally positioned to arrest or retard coin elements moving therein, manually operable means for effecting movement of said magnetic testing means from said normal position to effect release of coin elements arrested thereby, said chute having a normally closed movable side wall section arranged for movement into open position to provide a discharge passage adjacent said testing means and through which coin elements may normally escape when released as aforesaid, a second magnetic testing means spaced from said first-mentioned testing means at a point lower down said passage, and auxiliary ejecting mechanism including an ejecting member mounted for movement from a normal ineffective position into the chute passage to dislodge coin elements detained by said second testing means, and means operatively interconnecting said movable wall section, said manually operable means, and said auxiliary mechanism to actuate the latter and said ejecting member and open said discharge passage by operation of said manually operable means, and means arranged to selectively deflect coin elements in said passage at a point below said second testing means in cooperation with the latter.
3. A coin chute including a body providing a descending coin passage having an entrance and terminal exits, a first magnetic testing means movably mounted on said body near the upper region of said passage to arrest movement of certain coin elements, manually controlled means for moving said first testing means from a normal testing position to release arrested coin elements, means providing a drop-out exit from said passage between said entrance and terminal exits and adjacent said first testing means and through which released coin elements will ordinarily move as a result of movement of said testing means, such coins as do not ordinarily pass out through said drop-out exit continuing on down said passage, a second magnetic coin testing means arranged in a lower part of said passage for the purpose of arresting coin elements whether or not previously stopped by said first-mentioned test-

ing means and which fail to pass out said discharge exit, together with ejecting means including an ejecting arm pivotally mounted on said body for movement into and out of said coin passage adjacent said second testing means to engage and dislodge a coin element arrested by the latter for the purpose of effecting continued movement of such coin elements on down the passage toward said terminal exits, means normally urging said ejecting arm out of said passage, and mechanism operatively coupling said manually controlled means and said ejecting arm for coaction so as to effect movement of the first testing means out of said normal position into releasing position and move said ejecting arm into said passage for the purpose aforesaid, and selective coin deflecting means arranged in said passage below said second testing means for cooperation with the latter to selectively guide movement of coin elements relative to said terminal exits.

4. A coin chute including primary magnetic coin testing means for arresting coin elements of a predetermined character and arranged for clearing movement out of a normal testing position to free coin elements arrested thereby, means providing a discharge exit from said chute adjacent said primary magnetic testing means and through which freed coin elements normally pass from the chute, a main clearing mechanism arranged to effect clearing movement of the primary testing means as aforesaid, a second magnetic testing means spaced from said first-mentioned testing means at a point lower down said passage, a secondary clearing means including a sweep member mounted for movement from a normal ineffective position to a position in said chute near said secondary testing means and in the path of movement of coins moving toward said secondary testing means to engage and dislodge coin elements stopped by the latter, and terminal coin separating means cooperable with said secondary testing means to selectively guide the movement of coin elements after leaving said secondary testing means, together with mechanism coacting with said main clearing mechanism and said secondary clearing means to actuate the same in unison.

5. A coin chute comprising a chute body having a descending coin passage therein, a first magnetic testing means mounted on said body for movement toward and away from said passage and normally positioned close to the passage to arrest coin elements of a particular character, manually operable means for moving said testing means away from said passage to effect release of coin elements arrested as aforesaid, means providing a discharge passage leading from said coin passage near said first testing means and through which released coin elements normally pass, an intermediate magnetic testing device arranged at a lower point along said passage relative to said first-mentioned testing means, and also effective to arrest coins of predetermined character, ejecting means including a coin-engaging member mounted on said body for movement into and out of said passage adjacent said intermediate testing device to dislodge coin elements arrested thereby, means normally and yieldably positioning said coin-engaging member out of said passage, and means operatively associating said ejecting means for cooperation with said manually operable means whereby coin releasing and dislodging operation of said first testing means and ejecting operation of said coin-

engaging member may be effected at substantially the same time, together with terminal selecting means arranged to selectively guide movement of coin elements in the region of said passage below said intermediate testing device and in cooperation with the latter.

6. A coin chute mechanism comprising a chute body having a coin passage arranged therein for gravitating movement of coins, the upper end 10 of said passage constituting an entrance and there being a plurality of coin exits at the lower end of the passage, a first magnetic testing means and means movably mounting the same on said chute body adjacent said entrance in a normal 15 position to arrest the movement down said passage of coin elements of a predetermined character, means arranged and constructed to form a movable normally closed side portion of said passage opposite said first testing means and 20 which is opened to provide a discharge passage, said first testing means being moved from normal testing position to release an arrested coin element, operating mechanism arranged to move said movable side portion and said first testing 25 means from normal position as aforesaid to effect release of an arrested coin element, said element normally passing out said discharge passage, a second magnetic testing means arranged at a lower level than said first testing means and of 30 a type adapted to arrest coin elements of a predetermined character in said chute, and auxiliary ejecting mechanism arranged for coaction with said operating mechanism and including an ejecting member mounted on said body for movement 35 from a normally ineffective position into said passage in the region near said second testing means to engage and dislodge an arrested coin element in said region to effect continued movement of the dislodged coin element on down said passage toward said exits, together with means in 40 said passage in the region below said second testing means and cooperable with the latter to selectively guide the movement of coin elements relative to said exits.

7. A coin chute mechanism comprising a body member having a chute passage disposed for gravitating descent of coin elements therein, a magnetic member pivotally mounted on said body member and having a part extended into said chute passage for contacting attraction of coin 50 elements, manually operable means for pivoting said magnetic member out of said passage, magnetic means supported by said body member adjacent a lower region of said passage for maintaining a magnetic flux thereacross, ejecting means including a finger pivotally mounted on said chute body for movement into said passage adjacent said last-mentioned magnetic means to dislodge coin elements retained by the latter, and driving connections between said finger and said 55 manually operable means whereby said finger may be moved in ejecting action simultaneously with the movement of said first magnetic member.

8. A coin chute mechanism comprising a chute body having a descending coin passage therein with a plurality of exits, a magnetic member 60 movably mounted on the wall of said body normally to extend into said passage for attracting engagement with coin elements, manually operable means for withdrawing said magnetic member from said passage, fixed magnetic means spaced away from said first magnetic member to selectively influence movement of coin elements in 65 said passage, ejecting means including an eject-

ing member pivoted on said body and having a portion for extension into said passage to dislodge coin elements retained by said second magnetic means, a driving linkage connecting said ejecting member with said manually operable means whereby the operation of the latter will withdraw 6 10 said first mentioned magnetic member from said passage and simultaneously move said ejecting member into said passage, said linkage including a member extended through said body into said passage below said ejecting member for movement by operation of the linkage into the path of a coin dislodged by the ejecting member to deflect such coin toward a determined one of said exits.

9. A coin chute mechanism including a chute body comprised of a main body plate having channeled portions therein and a closure plate therefor defining in assembled relation a coin 15 passage in said body, a magnetic member pivotally mounted on a wall of said body and having a portion extended into said passage for contacting attraction of coin elements thereagainst, means for moving said magnetic member out of said passage including a lever pivoted on the body 20 and having a part engageable by manually operable driving means, a second magnetic member adapted to maintain a constant magnetic field across a part of said passage to selectively influence movement of coin elements therein, ejecting 25 mechanism including a finger mounted on said body for pivotal movement between said main plate and said closure plate into said passage adjacent the said second magnetic means to dislodge a coin element retained by the latter, and a driving linkage operatively supported on said body for pivoting said ejecting finger, said linkage including a deflecting member extended from a part thereof into said passage and a member 30 operatively engageable by said lever when the latter is pivoted by said manually operable means, whereby said finger will be pivoted into said passage and said deflecting member will be moved by said linkage into deflecting position in said 35 passage.

10. A coin chute mechanism including a chute body having a descending coin passage with an exit therein, a magnetic detecting member in communication with said passage, manual means for moving said member out of said passage to release coin elements attracted thereto, a second magnetic member supported on said body outside of said passage but maintaining a magnetic field thereacross, ejecting means supported by said body and including a pair of members movable into said passage adjacent said second magnetic means, one of which members is adapted to dislodge coin elements arrested by said last-mentioned magnetic means and the other of which members is adapted to deflect the movement of a coin, dislodged by the first member of the pair, toward said exit, and means drivingly connecting said ejecting members with said manually operable means whereby the operation of the latter will pivot said first magnetic means out of said 40 passage and move said ejecting members into the 45 passage.

11. A coin chute structure comprising a chute body having a tortuous chute passage with an entrance and an exit zone therein, a magnetic 50 device pivoted on an outer wall of said body and having a part normally extended into said passage for arresting the movement of paramagnetic coin elements therein, means providing an ejecting exit opposite said extended part of the mag- 55 60 65 70 75

netic device in the passage wall, closure means movably mounted on said chute and normally closing said ejecting exit, a second magnetic device supported on an outer wall of said body out of said passage but adapted to maintain a magnetic field across the passage to influence the movement of descending coin elements, and manually operable lever means for simultaneously moving said closure means to open said ejecting exit and pivot said first magnetic member out of the chute passage to dislodge coin elements retained thereby for discharge movement toward and through said opposite ejecting exit, and means including a first ejecting member pivoted on said chute body for movement by a slideable driving bar into said passage in the region of said second magnetic device for the purpose of contacting and dislodging coin elements retained in the passage by said second magnetic device, together with a driving connection between said driving bar and said manually operable lever means for actuating said first ejecting member and said first magnet member at substantially the same time, and a second ejecting member arranged for cooperation with said slide bar to be projected into said passage below said first ejecting member into the path of a dislodged coin to deflect the latter relative to said exit zone, substantially at the time said ejecting member is moved as aforesaid.

12. A coin chute mechanism comprising a chute

body having a descending coin passage therein and terminating in a plurality of exit zones, a magnetic member movably mounted on said body and having a part projecting into said passage for contact attraction of coin elements, means for moving said magnetic member out of said passage including a lever pivoted on said body and arranged for operation by manual control means, a second magnetic member located outside of said passage at a point below said first magnetic member, manually operable ejecting means including an ejecting finger pivotally mounted on said body for movement into said passage adjacent said second magnetic member to dislodge coins held by the latter, means for pivoting said finger including a bar member slideable on said body and linked with said finger to pivot the latter, said bar member having a deflecting pin projected into said passage at a point below said finger, the said pin being adapted to be moved relative to said passage to deflect a dislodged coin toward one of said exits when said bar member is operated to move said finger, and a driving linkage connecting said slideable bar and said aforementioned lever for substantially simultaneous operation by the latter with the movement of said first mentioned magnetic member.

WALTER A. TRATSCH.
WILLIAM PATZER.
